DESIGN FOR A TOY CANNON

Chauncey C. Sommerville and George H. Cook,
Seattle, Wash.

Application August 21, 1935, Serial No. 58,228

Term of patent 3½ years

To all whom it may concern:

Be it known that we, Chauncey C. Sommerville and George H. Cook, both citizens of the United States, residing at Seattle, in the county of King and State of Washington, have invented a new, original, and ornamental Design for a Toy Cannon, of which the following is a specification, reference being had to the accompanying drawing forming a part thereof.

In the drawing: Figure 1 is a view in side elevation of a toy cannon embodying our design.

Fig. 2 is a plan view of the same.

Fig. 3 is an end elevation of the same.

We claim:

The ornamental design for a toy cannon as shown.

CHAUNCEY C. SOMMERVILLE.
GEORGE H. COOK.
